UNITED STATES PATENT OFFICE.

MAX GARBELL, OF CHICAGO, ILLINOIS, ASSIGNOR TO VICTOR ADDING MACHINE COMPANY, OF CHICAGO, ILLINOIS, A CORPORATION OF ILLINOIS.

TYPEWRITER-CARRIAGE-LOCKING MEANS.

Application filed May 11, 1925. Serial No. 29,334.

These improvements relate to means for locking the carriage of a typewriter in some predetermined relative position in its longitudinal path of travel. In the present specific embodiment the typewriter fragmentarily shown may be considered to be one of the well-known relatively small kind adapted to be carried about conveniently in a closely-fitting case comprising a base board and a cover having a top wall and depending end and side walls.

In such so-called "portable" typewriters the carriage must be adjusted rather accurately in a middle position before the top cover or main housing part of the case can be affixed to the base board on which the machine ordinarily rests and which, as stated, forms a wall of the case.

It has been suggested heretofore to provide a lock for the carriage in its middle position, with means also for holding the rack out of engagement with the pinion controlled by the escapement mechanism.

The chief objects of these improvements are to provide means whereby the locking and unlocking of the carriage, for instance in its middle position, is simplified and rendered more rapid, more easy, and in general more satisfactory to the user; to provide carriage locking means of a peculiarly strong and positive character whereby certain of the typewriter parts are peculiarly well protected against otherwise injurious shocks and strains; to provide carriage locking and rack-releasing means substantially simultaneously put into operation in a simple and easy way, and without any manual control of the carriage, so as to provide substantially an automatic adjustment and locking of the carriage in its desired position, with the rack held out of contact with the escapement device pinion, and, in the structure shown, by merely depressing a key; and to provide means having the described advantages and which are equally operable when the carriage is in its shifted and in its non-shifted relative position. Other objects and advantages will appear hereinafter.

In the accompanying drawings forming a part hereof, Figure 1 is an enlarged vertical sectional view on the line 1-1 of Fig. 2, showing only that part of the typewriter mechanism more directly involved in the present invention; Fig. 2 is a fragmentary rear elevation of parts shown in Fig. 1; Fig.

3 is a front elevation of certain details of the locking mechanism; Fig. 4 is a vertical sectional view on the line 4-4 of Fig. 3; and Fig. 5 is a view taken on line 5-5 of Fig. 4.

The main frame 10 of the typewriting machine has a shaft 11 pivotally mounted therein and on which shaft is secured the carriage supports 12, (Fig. 1) only one thereof being shown. Secured to the carriage supports 12 is a lower guide rail member 13 having guide portions 14 and 15 adapted to coact with the companion guide member 16 having guide portions 17 and 18. The oppositely-disposed guides 14 and 17 and those marked 15 and 18 form guideways for sets of rollers 19 and 20 providing for the easy travel of the carriage from side to side of the machine.

Secured to the carriage base-plate 16, arcuate in cross section, are the carriage ends 21 in which is rotatably mounted a platen 22 positioned to receive the impact of the downwardly-and-rearwardly-striking type-bars 23, as shown in Fig. 1. Also pivotally mounted in the carriage ends 21 and rearward of the platen 22 is a shaft 24 extending longitudinally of the carriage and which has fixed thereto a downwardly-extending arm 25 enlarged at its lower end for the screws 26 threaded into the rack 27. The openings in the arm 25 through which the screws 26 pass are of a sufficient diameter to permit adjustment of the rack 27 with respect to the pinion 28 of the escapement mechanism. The arm 25 has an upwardly-extending thumb-piece 25^a to which the tension spring 29 is attached for holding the rack 27 retractably in engagement with the escapement pinion 28. The rack 27 is limited in its inward movement by the guide-rail 17, as shown in Fig. 1.

Pivottally mounted on the shaft 11 is a carriage-lock holding and guiding member 30 having at its lower end two inwardly-turned ears 30^a through which the shaft 11 extends. The side edges of the upper portion of the guide member 30 are formed into channel-shaped guides 31. As will be seen in Fig. 2 the guide member 30 is forked, providing the opening or recess 32 and the two upwardly-extending arms 33, these arms having outwardly-turned flanges 34 which are secured to the lower guide-rail member 13 (Fig. 1). Slidably mounted within the guide-member 30 is a similar member 35 having its sides formed into channel-shaped guides 36.

adapted to receive the slidably mounted stop or latch member 37.

The guide member 30 has at its lower end an outwardly turned ear 30^b to which one end of a tension spring 38 is secured, the other end of the spring being secured to the outwardly-extending ear 35^a formed at the lower end of the slidable member 35 projecting through the recess or opening 32 between the upwardly-extending arms 33 and limited in its downward movement by the metal at the bottom of the opening 32 at 30°. The slidable member 35 is provided with an inwardly-extending lug 35^d (Fig. 3), the top end of which is bent outwardly, forming an ear 35^e, said ear being perforated to receive one end of a tension spring 39, the other end of which is secured to the extending ear 37^a of the slidable stop member 37. This member 37 is limited in its upward movement by the lower edge of the guides formed on the sides of the slidable guide member 35, the body of which has an elongated slot 37^b (Figs. 3 and 4).

Adjacent to the guide member 30 is the rack-releasing member 40 having two inwardly-turned ears 41 and 42 through which the shaft 11 extends. The rack-releasing member 40 extends upwardly and has its top edge bent over at a right angle and to which bent-over part the pad or cushion 40^b is fixed, the pad being adapted to contact the rack 27.

The rack-releasing mechanism mounted on the shaft 11 is held in position by the collars 43 fixed to the shaft.

The base of the guide-rail member 16 has a downwardly-extending lug 44 fixed thereto and adapted to be engaged by the slidable and downwardly yielding locking member or part 37.

The key member 45 is pivotally mounted on the shaft 46, supported in the bearing member 47 fixed to the main frame 10 of the machine, the forward end extending through a slot in the comb 48 and being guided therein. The rearward end of the key member 45 has an arcuate upwardly-projecting arm 45^a extending through an elongated slot 37^b of the slidable stop member 37 and engages the slidable guide member 35.

The lower rear portion of the key member 45 has an arm 45^b bent at a right angle thereto and adapted to engage the extension 42^a formed on the ear 42 of the rack-releasing member 40.

The forward end of the key member 45 is provided with spring-actuated holding means comprising an arm 49 having a hook 49^a adapted to engage a recess in the comb 48 when the key member 45 is depressed. The thumb-piece 49^b on the arm 49 provides means for releasing the key from its carriage-locking position.

When the parts are in their unlocked position, as shown in full lines in Fig. 1, the upper portion of the carriage containing the platen

is free to move longitudinally step-by-step as the machine is operated.

Upon depressing the front end of key member 45 its rearward end or arcuate arm 45^a lifts the slidable guide member 35 carrying, through the tension of the spring 39, the slidable stop, catch or locking member 37 into the path of movement of the projection 44 on the carriage. The spring 39 then holds the catch 37 yieldingly in raised position. About midway of the upward movement of the arm 45^a the lower extension 45^b of the lever 45 engages the extension 42^a of the rack-releasing member 40 (see Fig. 1) and further movement of the key member 45 causes said member 40 to swing on the shaft 11 and into contact with the rack 27, forcing it out of engagement with the pinion 28, controlling the step-by-step movement of the carriage, thus freeing the carriage to be drawn by the motor drum until the stop or projection 44 contacts the beveled top of the latch 37, forcing it downward and permitting the stop 44 to advance slightly farther until it is opposite the recess 33 in the top of the locking part 37, at which time the spring draws the locking part 37 upward and the projection 44 becomes held within the recess 33. The carriage is thus not merely stopped but is locked against longitudinal movement in either direction.

It is thus clear that when the operator desires to lock the carriage in its medial position, regardless of its then position, he depresses the key K which automatically becomes caught and held in depressed position. As a result of this action the yielding latch 37 is raised into the path of the lug 44 on the carriage and the rack is moved out of engagement with the escapement device pinion, freeing the carriage for longitudinal movement in either direction. If the carriage is standing to the left of its middle position the operator merely pushes it to the right until it becomes locked, and if it is to the right it automatically moves to the left under the action of the motor drum and automatically becomes locked.

In the present machine the carriage is mounted on the shaft 11 for arcuate swinging movements backward and forward for engagement with spaced-apart characters on the type-bars respectively, for instance, lower case and upper case letters. The arcuate extension 45^a of the key member 45 has its effective top surface concentric with the arcuate shifting movement of the carriage, and the effect of depressing the key K is therefore the same whether the carriage be in its shifted or its non-shifted position.

Features of improvement disclosed but not claimed herein are reserved for a separate application or separate applications for patent thereon.

I contemplate as being included in the 130

present claimed invention such changes, modifications and departures from what is specifically set forth herein as fall within the scope of the appended claims.

5. I claim:

1. In a typewriting machine having a longitudinally movable carriage, the combination of a rack bar movable with respect to the carriage, a key-member mounted independent of the carriage, means for releasably locking the carriage against longitudinal movement, and means actuatable by the key-member regardless of the position of the carriage for moving the rack bar and positioning the locking means to be engaged by the carriage.

2. In a typewriting machine having a longitudinally movable carriage, the combination of a rack bar pivoted for movement relative to the carriage, a key-member carried by relatively fixed parts of the machine, means movable into the path of travel of the carriage for locking the carriage against longitudinal movement, means actuatable by the key-member regardless of the position of the carriage for positioning said movable locking means in the path of travel of the carriage and moving the rack bar, and means for maintaining the key-member releasably in a given position to maintain the locking means releasably in carriage-locking position.

3. In a typewriting machine having a longitudinally movable carriage, the combination therewith of a key-member operable from the front of the machine, carriage-locking means mounted to be moved toward the path of travel of the carriage, spring means for drawing the carriage in one direction, a rack on the carriage for providing a step-by-step movement of the carriage, a control pinion for said rack, means operable by a movement of the key-member for moving the locking means toward the path of travel of the carriage, means operable by the same movement of the key-member for disengaging the rack from its control pinion whereby the carriage is free to be drawn into contact with the locking means by the carriage-drawing means, the carriage and said locking means having cooperating elements including a spring-pressed member adapted to hold the carriage against longitudinal movement.

4. In a typewriting machine having a longitudinally movable carriage, means for drawing the carriage in one direction, locking means including a yielding member mounted for movement into the path of travel of the carriage, pinion-and-rack means for controlling the movement of the carriage, said rack being mounted for movement into and out of engagement with the pinion, means including a finger piece near the front of the machine for moving said yielding member into the path of travel of the carriage and for moving the rack out of engagement

with the pinion, and means or holding the rack and said yielding member releasably in said last-mentioned relative positions respectively.

5. In a typewriting machine having a longitudinally movable carriage, a pinion and rack for controlling the longitudinal movement of the carriage, locking means mounted for movement into the path of travel of the carriage, said rack and pinion being movable relatively to each other to disengage one from the other, and means operable regardless of the position of the carriage for simultaneously moving the locking means into the path of travel of the carriage and causing the disengagement of said rack and pinion.

6. In a typewriting machine having a longitudinally movable carriage, a pinion and rack means for controlling the longitudinal movement of the carriage, locking means mounted for movement into the path of travel of the carriage, said rack and pinion being movable relatively to each other to disengage one from the other, means for moving said locking means into the path of travel of the carriage, and means for causing the disengagement of the rack and pinion, said last named means being movable by said means for moving said locking means regardless of the position of the carriage.

7. In a typewriting machine having a longitudinally movable carriage, a pinion and a pivoted rack for controlling the longitudinal movement of the carriage, locking means mounted for movement into the path of travel of the carriage, said rack and pinion being movable relatively to each other to disengage one from the other, and means operable regardless of the position of the carriage for moving the locking means into the path of travel of the carriage and causing the automatic disengagement of said rack and pinion.

8. In a typewriting machine having a longitudinally movable carriage, a pinion and a pivoted rack for controlling the longitudinal movement of the carriage, locking means mounted for movement into the path of travel of the carriage regardless of the position of the latter, and pivoted means operable by said last mentioned means for engaging said rack and moving said rack on its pivot out of engagement with said pinion.

9. In a typewriting machine having a longitudinally movable carriage, a pinion and a pivoted rack for controlling the longitudinal movement of the carriage, locking means mounted for movement into the path of travel of the carriage, means for moving the locking means into the path of travel of said carriage regardless of the position of the latter, and pivoted means operable by said last mentioned means for engaging said rack and simultaneously moving said rack on its pivot out of engagement with said pinion.

10. In a typewriting machine having a lon-

- 5 longitudinally movable carriage, a pinion and a pivoted rack for controlling the longitudinal movement of the carriage, a locking means including an element movable into the path of the travel of said carriage, said element being yieldable when in said last mentioned position, a key-lever for moving said locking means into said position, and means engageable by the key-lever for actuating the pivoted rack and releasing said rack and pinion.
- 10 11. In a typewriting machine having a longitudinally movable carriage, means for controlling the longitudinal movement of the carriage, a locking means for locking the carriage against longitudinal movement, a key-lever for actuating said locking means, said locking means including a member movable towards the carriage, and an element carried by said member, said element being movable into the path of travel of said carriage regardless of the position of the latter.
- 15 12. In a typewriting machine having a longitudinally movable carriage, means for controlling the longitudinal movement of the carriage, a locking means for locking the carriage against longitudinal movement, a key-lever for actuating said locking means, said locking means including a member movable towards the carriage and an element carried by said member, said element being movable into the path of said carriage regardless of the position of the latter, and means for causing the release of said first mentioned means, said means being operable by said key-lever.
- 20 13. In a typewriter adapted to be encased and in which it is necessary that the movable parts thereof be located in predetermined minimum volume-occupying space prior to encasement, a longitudinally movable carriage, and key operated means for releasably locking said carriage in position for encasement, said means comprising a member positionable to retain said carriage in a predetermined position irrespective of the position in which said carriage may stand when said locking means are operated.
- 25 14. In a typewriter adapted to be encased and in which it is necessary that the movable parts thereof be located in predetermined minimum volume-occupying space prior to encasement, a longitudinally movable carriage, and key operated means for centralizing and locking said carriage.
- 30 15. In a typewriter adapted to be encased and in which it is necessary that the movable parts thereof be located in predetermined minimum volume-occupying space prior to encasement, a longitudinally movable carriage, and key operated means for centralizing and locking said carriage, said key operated means being so combined with said carriage that the latter may be locked in central position in either of its shifted positions.
- 35 16. In a typewriter adapted to be encased and in which it is necessary that the movable parts thereof be located in predetermined minimum volume-occupying space prior to encasement, a longitudinally movable carriage, and key operated means for centralizing and locking said carriage, said key operated means comprising a member tiltable in the same relation as said carriage to permit central locking of said carriage in either of its shifted positions.
- 40 17. In a typewriter adapted to be encased and in which it is necessary that the movable parts thereof be located in predetermined minimum volume-occupying space prior to encasement, a longitudinally movable carriage, and key operated means for locking said carriage in central position prior to encasement, said means permitting said locking irrespective of on which side of the center said carriage stands when said key is operated.
- 45 18. In a typewriter adapted to be encased and in which it is necessary that the movable parts thereof be located in predetermined minimum volume-occupying space prior to encasement, a longitudinally movable carriage adapted to be normally actuated by a rack and pinion, and key operated means for releasing said carriage from said normal rack and pinion connection and automatically setting up a central positioning lock for said carriage.
- 50 19. In a typewriter adapted to be encased and in which it is necessary that the movable parts thereof be located in predetermined minimum volume-occupying space prior to encasement, a longitudinally movable carriage adapted to be normally actuated by a rack, pinion, and power means, and key operated means for releasing said carriage from the normal rack and pinion connection to permit the free movement of said carriage in either direction, and means comprising a lock adapted to engage said carriage and automatically centralize the same when said carriage is moved in either direction after said release.
- 55 20. In a typewriter adapted to be encased and in which it is necessary that the movable parts thereof be located in predetermined minimum volume-occupying space prior to encasement, a longitudinally movable carriage, a depressible key member mounted on said machine, a member for locking said carriage in central position, and means operable upon depression of said key to free said carriage for movement in either direction and to so position said locking means that said carriage will be engaged and held in central position until the release of said key, irrespective of in which direction said carriage is moved to locked central position.
- 60 21. In a typewriter adapted to be encased and in which it is necessary that the movable parts thereof be located in predetermined minimum volume-occupying space prior to en-

- casement, a longitudinally movable carriage, a carriage centralizing and locking key, locking means operated by said key for arresting and holding said carriage in centralized position after the same is freed to be moved in either direction toward said central position; an engageable portion on said carriage, said locking means comprising an engaging member adapted to be lifted into the path of said carriage portion, said engaging member being so contoured and mounted that it will engage and lock said carriage in central position when the latter is moved from either direction toward the center.
- 15 22. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position.
- 20 25. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position; an engageable portion on said carriage, a yieldingly mounted equitant member adapted to embrace said carriage portion to lock the latter and having cam-like sides to permit the carriage portion to ride thereover and be embraced and locked irrespective of the direction in which said carriage is moved after being freed.
- 25 23. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion.
- 30 24. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion.
- 35 25. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion, said locking member being forked to receive said carriage portion between its arms and said arms being cam-like so that said carriage portion may yieldingly press said locking member to lock said portion between said arms irrespective of the direction said carriage moves.
- 40 26. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion, said locking member being forked to receive said carriage portion between its arms and said arms being cam-like so that said carriage portion may yieldingly press said locking member to lock said portion between said arms irrespective of the direction said carriage moves, and said key being releasably held in locked position upon depression to secure said carriage against longitudinal movement.
- 45 27. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion, said locking member being forked to receive said carriage portion between its arms and said arms being cam-like so that said carriage portion may yieldingly press said locking member to lock said portion between said arms irrespective of the direction said carriage moves, and said key being releasably held in locked position upon depression to secure said carriage against longitudinal movement.
- 50 28. In a typewriter adapted to be encased and in which it is necessary that the movable parts thereof be located in predetermined minimum volume-occupying space prior to encasement, a longitudinally movable carriage, a carriage centralizing and locking key, locking means operated by said key for arresting and holding said carriage in centralized position after the same is freed to be moved in either direction toward said central position, an engageable portion on said carriage, a guide member, a member slidable in said guide member, and a locking member movable with, but yieldingly mounted in, said slidable member, and means operated by said key to move said slidable member and said locking member into the path of said carriage portion, said locking member being forked to receive said carriage portion between its arms and said arms being cam-like so that said carriage portion may yieldingly press said locking member to lock said portion between said arms irrespective of the direction said carriage moves, and said key being releasably held in locked position upon depression to secure said carriage against longitudinal movement.

MAX GARBELL.
